(57) **CLAIM**

The ornamental design for an arbor for a circular saw, as shown and described.

DESCRIPTION

FIG. 1 is an exploded top and front perspective view of an arbor for a circular saw showing my new design relative to an environmental circular saw;

FIG. 2 is an assembled top and front perspective view thereof in conjunction with an environmental circular saw;

FIG. 3 is an assembled top and front perspective view thereof;

FIG. 4 is a rear perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top and front perspective view of the female component of the arbor for a circular saw in FIGS. 1-8; and,

FIG. 10 is a top and rear perspective view of the male component of the arbor for a circular saw in FIGS. 1-8.

The broken line showing the circular saw blade is provided

for the purpose of illustrating environmental structure and

forms no part of the claimed design.
